William Wallace Potter, Pawtucket, R. I.

Application May 16, 1947, Serial No. 139,085

Term of patent 14 years

(Cl. D85—2)

To all whom it may concern:

Be it known that I, William Wallace Potter, a citizen of the United States, residing at Pawtucket, in the county of Providence and State of Rhode Island, have invented a new, original, and ornamental Design for Combined Cigarette Extinguisher and Ash Tray, of which the following is a specification, reference being had to the accompanying drawing, forming part thereof.

In the drawing:

Figure 1 is a perspective view of a combined cigarette extinguisher and ash tray showing my new design; and

Figure 2 is a perspective view thereof, the component parts being separated.

I claim:

The ornamental design for a combined cigarette extinguisher and ash tray, as shown.

WILLIAM WALLACE POTTER.
